[57] CLAIM

The ornamental design for a combined golf tee, greens repair tool and golf club prop, as shown.

DESCRIPTION

FIG. 1 is a top plan view of a combined golf tee, greens repair tool and golf club prop showing my new design; FIG. 2 is a front elevation view thereof, the opposite side being a mirror image;

FIG. 3 is a bottom plan view thereof;

FIG. 4 is a top plan view with the tee shown in a collapsed position;

FIG. 5 is a front elevation view thereof, the opposite side being a mirror image;

FIG. 6 is a right side elevation view with the tee shown in an upright position;

FIG. 7 is a left side elevation view thereof; and,

FIG. 8 is a perspective view thereof.
